UNITED STATES PATENT OFFICE.

EDGAR R. JONES, OF KANSAS CITY, MISSOURI, ASSIGNOR OF ONE-HALF TO
E. H. L. THOMPSON, OF SAME PLACE.

TAG, BOX, OR SIGN STAMP.

SPECIFICATION forming part of Letters Patent No. 628,147, dated July 4, 1899.

Application filed February 25, 1898. Serial No. 671,687. (No model.)

To all whom it may concern:

Be it known that I, EDGAR R. JONES, of Kansas City, Jackson county, Missouri, have invented certain new and useful Improvements 5 in Tag, Box, or Sign Stamps, of which the following is a specification.

My invention relates to a tag, box, and sign stamp; and it consists, essentially, of two parts—one a type-magazine of peculiar construction and the other a type-galley provided with one or a plurality of grooves or channels either of which is adapted to register with a groove or channel of the magazine.

The invention further consists in certain 15 novel and peculiar features of construction and organizations of parts, as will be herein-after described and claimed.

The object of my invention is the provision of a magazine in which the type must be originally arranged right side up, but otherwise indiscriminately—that is to say, there need be no systematic or alphabetical or numerical arrangement—and a galley or stamp-block provided with a groove or grooves which shall 25 register with a channel of the magazine when it is necessary or desirable that type shall be transferred from the magazine to the galley, or vice versa.

Other objects of the invention will herein-after appear.

In order that the invention may be fully understood, I will proceed to describe it with reference to the accompanying drawings, in which—

Figure 1 represents a top plan view of a device embodying my invention. Fig. 2 is a vertical section taken on the line II II of Fig. 1. Fig. 3 is a cross-section of the galley or stamp-block, type being arranged in each groove of 35 the same. Fig. 4 is a vertical longitudinal section illustrating the style of galley or type-block employed when stamping boxes or any surface which may be rough or uneven. Fig. 40 5 is a perspective view of a block employed in securing the line of type at any desired point in the galley. Fig. 6 shows a pin or pointer by which any desired type may be quickly separated from the others in the magazine and positioned in the galley.

In the said drawings, 1 designates a block,

preferably of circular form and provided with an offset or projection 2 and with a pair of circular channels 3 and 4, respectively, in its upper side, said channels being arranged concentrically to each other. It is also provided 55 with a cross-channel 5, connecting channels 3 and 4, and with a curved channel 6, which communicates with channel 3 and forms practically a continuation of channel 5, said channel 5 registering with channel 6 and extending 60 at such an angle that a type may be transferred from channel 4 to channel 6, or vice versa, in a perfectly straight course in order that the transference of the type from the inner channel 4 of the magazine to the galley, 65 to be presently described, or vice versa, may be facilitated and accomplished without careful manipulation. The necks or upper ends of the various channels are contracted, preferably, by means of a thin metallic plate 7, secured by screws or equivalent means to the block. This plate, in view of the fact that it is slotted to form necks for the said channels, necessarily consists of three sections—7 to project 70 beyond the inner margin of channel 4, 8 75 to project inward and outward, respectively, of the outer and inner margins of channels 4 and 3 and inward of the margins of channel 5, and 9 to project inward of the outer margin of channel 3 and inward of both margins 80 of channel 6, as illustrated.

10 designates a spring which intersects channel 3 at its upper side, extending substantially parallel with channel 5, but arranged from the neck of said channel a distance at least equal to the space between one side of the channel and the corresponding side of its neck, for a purpose which will be 85 herinafter described. The spring is coiled, preferably, upon a pin 11, projecting from section 9 of the top plate, and has one end bearing against a pin 12 and its free end at the opposite side of said channel 4 against the pin 13, projecting from section 8 of the top plate, the arrangement being such that 90 the spring may swing to the position indicated by dotted lines in order to permit one or more type in channel 3 to pass by in the direction indicated by the arrow a. A similar spring 14 bridges the channel 5, being 95 100

coiled upon a pin 15 and resting against a pin 16 of section 8 of the top plate, while its free end bears against the pin 17 of said section, but at the opposite side of said channel, the arrangement being such that said spring may swing to the position shown in dotted lines, and thereby permit a type to pass freely from channel 4 through channel 5. To return said type, however, the spring must be sprung by hand outwardly to the position indicated; otherwise the type cannot pass through the passage 5.

18 designates a galley which is provided with one or more grooves 19 and which may be perfectly flat on top, as is desirable for printing tags and other flat surfaces, or arc-shaped, as indicated by Fig. 4, to print upon boxes and other surfaces which may be rough or uneven, and consequently require to produce a clear and legible impression a rocking or oscillatory movement, as will be readily understood. In this case also the end of the channel 6, which registers with one or another of the grooves of the galley, slopes upward, as at 6^a, to meet the grooves, which in this case parallel the curved or arc-shaped face of the galley. The grooves of the galley, like the channels of the magazine, are provided with contracted necks formed by securing to the block a top plate consisting of a series of strips 20, which project beyond the margins or sides of said grooves, as shown in the drawings.

In vertical alinement with the center of each groove and below the same the galley is provided with a longitudinally-extending hole 21 to receive snugly a pin 22, projecting from the extension 2 of block 1 vertically below the channel 6, and thereby hold in alinement with the last-named channel the groove of the galley vertically above the particular hole engaged by said pin. By this arrangement it is obvious that after a line of type is "set up" in any particular groove of the galley it may be slipped off said pin and a second groove be caused to register with channel 6 with practically no loss of time.

For use in connection with this device the usual rubber blocks carried in stock by those engaged in the manufacture and sale of rubber stamps and articles of kindred type are secured by glue or other material upon the upper ends of rectangular blocks 23, which blocks are adapted to fit snugly but slidingly in the various channels and grooves described, and said blocks in their inner and outer faces are grooved, as shown at 24, to provide a neck portion which will fit snugly but slidingly in the contracted necks of said channels and grooves, as shown clearly in Fig. 3. The fact that said blocks overlap the flanged edges of the top plates, as shown clearly in Figs. 1 and 3, explains the reason why the springs 10 and 14 must be arranged at some distance from the contiguous edge of the necks of said channels, as hereinbefore described. In other words, it would be impossible for said blocks

to pass unless said springs are set back the necessary distance. The blocks are also provided in their opposite sides and upper ends with semicircular notches 25, so that the two notches of the contiguous blocks shall register, and thereby form a conical hole or opening, into which may be inserted the attenuated end of a pointer 26, by which the particular type-block 23 or spacer-block 27 may be expeditiously separated from the remaining blocks and transferred to the galley, which operation is accomplished as follows—that is to say, if it be desired to dispose the block carrying the capital letter "R," for instance, in the registering groove of the galley the operator would insert the pointer in the hole between the type-blocks "R" and "S" and then, pressing against type-block "R," shove the whole series of type in advance of the same around in the direction indicated by the arrow *a* until type "R" occupied a position in line with the channel 5. He would then place the pointer in the hole at the opposite side of said type and shove it through channel 5 and channel 6 into the registering groove of the galley. This operation is repeated with each type, and in this manner any word or number or combination thereof may be set up in the galley in less time than it takes a skilled compositor to select the type from a box when mixed indiscriminately, but not when arranged in separate compartments, though it will be understood that shipping-clerks, for whose use this device is designed especially, are generally provided with only a single box, in which the type are indiscriminately arranged. This is the case because a shipping-clerk does not stand in one position all the time and it would not be convenient nor practicable for him to carry a large type-case every time he moved from one position to another.

In order to secure the line of type, I provide a series of blocks 28, which may also, if desired, be used as spacing-blocks. These blocks 28 are provided with cavities or holes 29 for engagement with the pointer 26 in order that they may be conveniently shifted from one position to another, and they are adapted to fit more snugly in the grooves of the galley than the magazine in order that by friction they may hold the line of type firm. Said blocks are inserted in grooves from the open ends of the latter because they are entirely below the series of strips 20, forming the top plate of the galley, and consequently can only be moved under longitudinally-applied force; but owing to the fact that they fit in said groove with more or less friction their accidental dislocation is prevented.

In practice the magazine preferably will be provided with two grooves, as shown in Fig. 1, one to contain a sufficient number of small letters to set up any address and the other, preferably the inner one, to contain capital letters and numbers in sufficient quantity.

Punctuation-marks may also be provided for, if desired; but these are not generally used, as the shipping-clerk leaves sufficient space between words to avoid confusion.

5 The spring 10 is designed to deflect a type when moved in the direction indicated by the arrow *b* into the channel 6, so that no particular care need be exercised in this operation and the work is facilitated. The type 10 is properly positioned in front of the channel 6 by the right-hand rotation of the line already described for the capitals. The spring 14 is designed chiefly to prevent a block traveling from channel 6, in the direction indicated by arrow *c*, from passing accidentally 15 through channel 5 into channel 4, though it is obvious that this spring may be dispensed with without affecting the speed to any appreciable degree. In fact, it may be found desirable 20 in practice to dispense entirely with the inner channel 4 and channel 5. By so doing the diameter of the magazine-block would be necessarily increased to contain the requisite number of blocks; but this objection 25 would be more than counterbalanced by the fact that there would practically be no chance for a block being deflected in the wrong direction by the guide-spring, as is now the case with respect to channel 4 and spring 14—that 30 is, to shove the type-block "E," for instance, from the channel 4 through channel 5 the spring 14 must yield, as its tendency is to deflect the block past the mouth of said channel and not into it.

35 From the above description it will be apparent that I have produced a device of the character described which embodies the features of advantage enumerated in the statement of invention and which is of simple, 40 cheap, and durable construction.

Having thus described the invention, what I claim as new, and desire to secure by Letters Patent, is—

45 1. A tag, box and sign stamp, comprising two members, one a magazine provided with an annular channel and a second channel communicating at one end with the annular channel, and the other a galley, provided with a groove adapted to register with the opposite 50 end of the last-named channel, blocks arranged to slide in said channels and groove and provided with type at their upper ends, and a spring intersecting the annular groove and adapted to guide type-blocks from said 55 groove into the communicating groove of the magazine when pushed in a certain direction, substantially as described.

2. A tag, box and sign stamp, comprising a magazine provided with an annular channel having a contracted neck at its upper edge, 60 a communicating channel provided also with a contracted neck, a galley provided with a groove registering with the last-named channel, also having a contracted neck, a sliding type-block adapted to work snugly in said 65 channels and groove and provided with a narrow neck portion embraced by the contracted neck of said channels and groove, and a guide-spring intersecting the annular channel and arranged to deflect a type-block when it is moved in a certain direction, substantially as 70 described.

3. A tag, box and sign stamp, comprising a magazine provided with an annular channel having a contracted neck at its upper edge, 75 a communicating channel provided also with a contracted neck, a galley provided with a groove registering with the last-named channel, also having a contracted neck, a sliding type-block adapted to work snugly in said 80 channels and groove and provided with a narrow neck portion embraced by the contracted neck of said channels and groove, and with notches or cavities in their upper ends and at opposite sides, and a guide-spring intersecting 85 the annular channel and arranged to deflect a type-block when it is moved in a certain direction, substantially as described.

4. A tag, box and sign stamp, comprising a magazine provided with an annular channel having a contracted neck at its upper edge, 90 a communicating channel provided also with a contracted neck, a galley provided with a groove registering with the last-named channel, also having a contracted neck, slid able 95 type-blocks adapted to work snugly in said channels and groove and provided with narrow neck portions embraced by the contracted neck of said channels and groove, and with notches or cavities in their upper ends and opposite sides, a guide-spring intersecting the 100 annular channel and arranged to deflect the type-blocks when they are moved in a certain direction, and a pointer having an attenuated end to separate and move the type-blocks from 105 one position to another, substantially as described.

In testimony whereof I affix my signature in the presence of two witnesses.

EDGAR R. JONES.
